FIRST AID KIT

Filed Aug. 24, 1927

FIG.-1.

FIG.-2.

FIG.-3.

INVENTOR.
James E. Harding
BY *P. Klein*
HIS ATTORNEY

UNITED STATES PATENT OFFICE.

JAMES E. HARDING, OF LYME, CONNECTICUT.

FIRST-AID KIT.

Application filed August 24, 1927. Serial No. 215,187.

This invention relates to first aid kits and more particularly to that general type which may be conveniently carried about in one's pocket.

5 One of the objects of the present invention is to provide a first aid kit of a small and compact size, which may be easily and conveniently carried about, and which will contain the usual medicinal or surgical paraphernalia 10 necessary for treating small wounds.

A further object is to provide a kit of the above general character having a plurality of compartments containing different materials or instruments, each of which is readily 15 accessible without disturbing the contents of the other compartments.

A further object is to provide a kit of the last above mentioned character which may be inconspicuously carried in one's pocket and 20 yet retain the contents thereof in a predetermined manner regardless of the position in which the kit is carried.

Other objects will be in part obvious and in part hereinafter pointed out in connection 25 with the accompanying sheet of drawings illustrating two of the various possible embodiments of the invention, and in the several views of which corresponding parts are indicated by similar reference characters.

30 In these drawings—

Fig. 1 is a longitudinal, sectional, elevational view of one form of the device;

Fig. 2 is an elevational view of the device shown in Fig. 1; and

35 Fig. 3 is a vertical, longitudinal, sectional view showing the modified form of the invention.

Referring now to the drawings in detail, and more particularly to Fig. 1, there is shown 40 in sectional elevation a substantially cylindrical, elongated casing, preferably formed of two main parts 5 and 6, having a coactive threaded connection at 7. The ends of these casing members are closed preferably by 45 screw caps 8 and 10 so that the entire casing as shown in Fig. 1 very much resembles an ordinary fountain pen. The materials used may be hard or semi-hard rubber or bakelite, for example, and the shape either cylindrical 50 or polygonal, altho, for convenience of manufacture and assembly, it is preferred to use the form shown in Fig. 2.

It will be noted in the modification shown

in Fig. 1 that the interior of the casing formed by the parts 5 and 6 are divided into a plurality of chambers separated, for example, by the frictionally held partition 11. In the upper chamber, there is provided a small scalpel 12 or other suitable small instrument depending upon the purpose to which the kit may be 55 specifically adapted. This chamber also contains gauze or cotton 13 and one or more medicated tablets 14. The lower chamber preferably contains a soft rubber, tubular member 15 having a nozzle 16 closed by a stopper 17.

The side of the casing is provided with a cut-away portion closed by the member 18. Thus, when the parts 5 and 6 are separated, the flexible container 15 may be filled with an 60 antiseptic or other fluid by pressing on the shim 18 before immersing the nozzle in the fluid, just as one fills a fountain pen. The stopper 17, which closely abuts the partition 11, is held in place by means of the partition 65 11, thereby preventing any leakage regardless of the position in which the kit may be resting.

A clip of any desired type, such as indicated at 20, is applied to the exterior of the 70 casing for holding the kit in one's pocket or supporting it from some other place, as desired.

The form shown in Fig. 3 is substantially 75 the same as that above described except that two partitions 21 and 22 are provided for dividing the interior of the casing into three 80 chambers. The upper chamber contains cotton or gauze 13, for example, as well as the medicated tablets 14. The central chamber 90 contains a small and preferably glass bottle 23 closed by a stopper 24 which is held tightly in place by the partition 21 when the parts are assembled. The lower partition 22 supports the lower chamber for containing 95 a roll of adhesive 25 and needle and thread 26. By reason of the unique and tubular construction of the outer casing, it will be immediately seen that access may be had to one of the compartments without 100 disturbing the contents of the other compartments. Thus, if it is desired to form a disinfecting solution by means of the medicated tablets 14, it is only necessary to remove the cap 8. On the other hand, if the 105 iodine or other antiseptic contained in the

bottle is needed, then the parts 5 and 6 are unscrewed and the stopper 24 removed. Likewise by removing the base cap 10, access to the adhesive tape or needle and thread 5 may be had.

- Of course, I do not wish to be limited to the particular arrangement of the surgical supplies named and illustrated, for obviously the compartments being of substantially the 10 same size and the removable partitions frictionally held in any desired position, the parts shown may be moved about or substituted for each other or different materials, as circumstances may require.
- 15 It is thus seen that the present invention provides a simple and practical first aid kit of ornamental yet inconspicuous form, which may be easily carried about in one's pocket. The invention is of simple and practical construction, may be inexpensively manufactured and assembled, and is well adapted to 20

accomplish among others all of the objects and advantages herein set forth.

I claim:

In a first aid kit, in combination, a two 25 part substantially cylindrical, tubular casing, the parts being provided with a threaded connection whereby they may be easily and quickly separated, means at the ends of said parts for permitting access thereto, a 30 frictionally held partition separating the interior of the casing into a plurality of chambers, one of which is adapted to contain a fluid container provided with a stopper, which stopper is held in place by said partition, and means whereby said fluid container may be filled without removing it from the casing comprising a depressible 35 portion on the casing.

In testimony whereof I affix my signature. 40

JAMES E. HARDING.
